LAVINA C. MILEY, OF WALLA WALLA, WASHINGTON

GARMENT SEPARATOR AND SIZE INDICATOR

Application filed May 19, 1928. Serial No. 279,108.

This invention relates to garment separators and size indicators, and is an article of manufacture, and is adapted to provide a signboard and a clamp practically from one 5 piece of metal.

Another object of the invention is to provide a garment separator and size indicator that may be movably and removably attached to a clothes pole, to separate and indicate the 10 sizes of the separated garments.

A further object of the invention is to provide a garment separator and size indicator that is cheap to manufacture and simple to install, and having a sign board that may be 15 further twisted or untwisted to position for the greatest visibility. A further object of the invention is to provide a garment separator and size indicator that may be easily removed for the purpose of cleaning the clothes 20 pole or for rearrangement.

With these and other objects in view reference is now had to the accompanying drawings in which

Fig. 1 is a perspective view showing the 25 application of the device;

Fig. 2 is an inverted front elevation of the device;

Fig. 3 is a front elevation of a blank from 30 which part of the device is made; and

Fig. 4 is a similar view to Fig. 3 showing a second member to be associated with the first portion and complete the clamp.

Having reference to the drawings like numerals refer to like parts throughout the 35 several views and the numeral 1 refers to a clothes pole upon which may be supported dresses 2, or other clothes for display, by coat hangers 3, or the like in the usual manner.

The pole 1 may be supported by any suitable means, which means is not shown as only a fragment of the pole is shown and as it is deemed unnecessary as such supporting structure is old in the art and has no bearing on 45 this invention, and hence needs no further description.

The invention comprises an article of manufacture whose novelty rests in its simplicity of construction; in its adaptability to 50 the purpose for which it is intended; in the

fact that a signboard 4 is provided which is a unit with a clamp 5, and its susceptibility to being twisted to set the signboard with respect to the clothes pole for greatest visibility.

The article consists primarily of the sign- 55 board 4 mentioned which is preferably of rectangular shape, and formed integral therewith is a clamp jaw 6 of simple construction and having its jaw portion curved and adapted to form with a second jaw 7, means to secure the device in an upright position, as shown in Fig. 1, on the clothes pole 1.

The views shown in Figs. 2, 3, and 4 represent the article and parts thereof in an inverted position from that of final use and this 60 positioning of the parts on the drawing merely represents the natural positioning in working out the layout preliminary to its manufacture, and in Fig. 3 is shown the layout of the signboard 4 and jaw 6 in which it will be 65 noted that two holes 8 are provided therein and within the confines of said signboard and the lines 9 extended upward from these holes and those lines 10 to the right and left respectively represent the cutting lines on 70 which the blank is cut preparatory to the construction of this device.

Extending upward from that part 11 of the signboard between the two holes 8, is a relatively narrow strip 12, which strip is 80 formed integral with said signboard through a neck portion 13; and this strip is adapted to provide a portion of the clamp 5 which is made part of the device.

The strip consists of the clamp jaw 6, 85 which will be curved as shown in Fig. 2, hinged portions 14 extended on either side of the strip to provide for hinging this part with the second part 7, to be described, and a lever part 15 for use in opening the clamp 90 and this part of the device is shaped for the purpose mentioned, in the following manner:

The hinged portions 14 are bent upward at right angles to the strip, the curved portion mentioned is curved in a similar upward manner on the outer end of the strip, and an upward bend is given to the lever part as shown at the point 16 in Fig. 2, and the neck 13 of the strip is formed within the cutting lines and extends upward from the holes to 100

receive a twist, as at 17, which places this portion of the clamp at right, or other suitable angles to the signboard.

The second member 7, used to complete the clamp, is constructed similar to the first mentioned strip 12 and is shaped in a like manner so that the hinged parts 18 will engage with the hinged parts 14 of the strip, and these two parts are joined together by means of a pin 19 upon which has first been placed a spring 20, shown dotted in Fig. 2, adapted to yieldingly maintain the completed clamp in a closed position.

By the assembling of these parts the clamp 5 is provided wherewith to secure the signboard in a rigid and upright position on the pole 1, and due to the relatively small neck and to the thinness of the material of which the device is constructed, the signboard may 10 be twisted to assume an angle with respect to the pole to present the signboard in the best position for observation.

In use the device is constructed as above outlined and suitable characters 21 may be placed upon the signboard, the device then being clamped upon the clothes pole there to prevent the hook of the coat hanger 3 from sliding past the clamp during the separation of the garments 2 for selection, and the 20 characters are intended to represent the sizes of garments contained within the limits of any two of the devices.

Obviously the characters used may designate sizes, or quality, or what not, and the signboard may be of a size to accommodate all the necessary printing thereon, and the printed matter may be placed thereon either by hand or other means as may be most convenient or desirable.

Having thus described my invention, I 40 claim

1. In a garment separator and size indicator, an article of manufacture comprising a signboard having an integral portion extended to form a portion of a clamp, said portion being provided with an initial twist to position said signboard at an angle with said clamp, said twisted portion being adapted to change said angle by further twisting or untwisting, and provided with a second member yieldingly and hingedly attached to said first mentioned portion to complete said clamp.

2. In a garment separator and size indicator, an article of manufacture comprising a signboard having an integral portion extended to form a portion of a clamp, and provided with a neck connecting said signboard and said portion, said neck having a twist positioning said signboard at an angle to said portion, and provided with a second member yieldingly and hingedly attached to said first mentioned portion to complete said clamp.

3. In a garment separator and size indicator, an article of manufacture comprising a

signboard having an integral portion extended to form a portion of a clamp, and provided with a neck defined by slits cut in said signboard and connecting said portion and said signboard, said neck being adapted to be twisted to position said signboard at an angle to said portion, and provided with a second member yieldingly and hingedly attached to said first mentioned portion to complete said clamp.

In testimony whereof I affix my signature.

LAVINA C. MILEY.
